ATTORNEY

UNITED STATES PATENT OFFICE

JOHN C. BREHM, OF BAYONNE, NEW JERSEY

BEATER ATTACHMENT FOR VACUUM CLEANING MACHINES

Application filed March 23, 1928. Serial No. 264,236.

This invention relates to vacuum cleaning machines and particularly to the provision of a beater attachment for machines of the class specified; and the object of the invention is to provide a beater attachment in the form of a nozzle adapted to be moved over a surface to be cleaned, the open end of the nozzle having a beater member arranged therein and adapted to be actuated inwardly and outwardly with respect to the opening of the nozzle to engage and strike a surface to be cleaned, to raise the dust from such surface to be drawn through the nozzle into the dirt receiving receptacle of the cleaner, facilitating the more thorough cleaning of rugs, carpets, cushions and like coverings and facings; a further object of the invention being to provide a nozzle of the class specified which may, by virtue of its construction, be universally adapted to many of the standard makes of vacuum cleaning apparatus and including means for placing the beater element or member in operative connection with a rotatable or other operable member of the vacuum cleaning apparatus, said beater element being positively moved in one direction and tensionally operated in the other direction; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view, diagrammatically illustrating a part of a vacuum cleaning apparatus, and showing one of my improved nozzles mounted in connection therewith.

Fig. 2 is a section on the line 2—2 of Fig. 1; and,

Fig. 3 is a face view of a part of the apparatus shown in Fig. 1 and with part of the construction broken away.

In the drawing, I have shown for the purpose of illustrating one use of my invention,

a vacuum cleaning apparatus 5 of a conventional type consisting of a fan or suction casing 6 in which a fan 7 is rotatably mounted. The fan is driven by an electric motor contained in the casing portion 8 of the apparatus, the casing 6 having a tube 6^a leading therefrom with which the bag or dust receiving receptacle 9 is coupled. The apparatus is mounted on suitable wheels 10 facilitating its free movement over a floor or other surface. 55

In the construction shown, the usual suction nozzle of the machine has been removed or detached as is customary in many standard types of machines and substituted therefor is my improved beater attachment 11 comprising a casing, one end 12 of which is tubular in form and flanged as seen at 13 to be mounted and coupled with the casing 6 to bring the tube 12 in alignment with the aperture 6^b opening outwardly through the casing and 70 into the fan or suction chamber thereof. The free end of the beater casing 11 flares laterally and downwardly to form a comparatively wide and elongated nozzle end 14 which is movable over the surface to be cleaned, this 75 open end being directed downwardly in the manner of other nozzles of this type.

Mounted in suitable bearings 15 and 16 within the upper end portion of the casing 11 is a shaft 17, the outer end of which is provided with a coupling 18 adapted to engage the fan 7 or the shaft of said fan whereby the rotation of the fan will correspondingly rotate the shaft 17. Secured to the shaft 17 is a cam wheel 19, the cam surface 19^a of which 80 is arranged on one side of the wheel 19 and is adapted to actuate an arm 20 to correspondingly operate a beater element 21. The upper end of the arm 20 preferably carries an anti-frictional bearing member 20^a, which rides over the cam surface 19^a, the latter being of such contour as to gradually raise the beater element 21 or draw the same into the neck portion 14 and out of engagement with a 85 surface to be beaten or cleaned and to release the arm suddenly, whereby the spring member 21^a of the beater element which has been placed under tension in the above operation actuates to suddenly move the element 21 into 90

engagement with the surface to be cleaned as will be apparent.

In the construction shown, the beater element 21 is fashioned from wire bent into 5 comparatively wide and flat coil portions 21^b which may be described as of sinusoidal or serpentine form which extend substantially through the entire area of the open end of the member 11 or the nozzle 14 thereof, and 10 the wire from which the element 21 is formed is coiled about a rod or shaft 22 as seen at 22^a, note Fig. 2. In the construction shown, the spring member 21^a constitutes an integral part of the wire employed in said coils and 15 engages one wall of the nozzle 14 as clearly seen in Fig. 1 of the drawing. It will also be noted that the lower end portion of the arm 20 is yoke-shaped in form, being also constructed of wire, and the ends of said 20 wire are wound around the rod 22 and have portions 23 engaging parts of the coils 21^b to raise the same against the tension of the spring member 21^a as above described. The central portion of the arm 20 also prefer- 25 ably passes through a yoke-shaped guide and stop member 24, constituting part of the attachment 11.

From the foregoing, it will be apparent that in the operation of the vacuum cleaning 30 apparatus, with my improved attachment mounted in connection therewith, the rotation of the fan or suction element of the machine will transmit movement to the beater element 21 through the cam 19 and arm 20 35 to intermittently and repeatedly raise said element, the beating action to the element being transmitted by the spring member 21 to lightly and yet effectively raise the dust that may be contained in a carpet, rug, pil- 40 low, cushion or the like, or upholstery of chairs, vehicles and other apparatus. As the dust is raised from the member being cleaned, it is sucked through the attachment and collected in the receiving receptacle 9.

45 It will be understood that my invention is not necessarily limited to the specific structure of beater element herein shown and described, nor to the specific means of actuating a beater element, nor is my invention 50 necessarily limited to the specific general contour of the attachment disclosed. Various changes in and modifications of the construction herein set out may be made within the scope of the appended claims, 55 without departing from the spirit of my invention or sacrificing its advantages.

Having fully described my invention, what I claim as new and desire to secure by Letters Patent, is:

60 1. In a vacuum cleaning apparatus having a suction nozzle in communication with the suction creating means of the apparatus, a beater element arranged at the open end of said nozzle and adapted to oscillate in- 65 wardly and outwardly with respect to the

open end of said nozzle, on an axis arranged longitudinally of said element and at one side of said nozzle, means in operative connection with a driven member of the apparatus for actuating said element in one direction, tensional means for actuating the element in the opposite direction, and said beater element comprising a span of wire of sinusoidal form.

2. In a nozzle for vacuum cleaners having 75 an opening adjacent the surface to be cleaned, a beater mounted in said nozzle to move inwardly and outwardly through said opening, means for actuating said beater, and said beater element involving a span of wire of 80 sinusoidal form disposed over substantially the entire area of said opening.

3. In a nozzle for vacuum cleaners having 85 an opening adjacent the surface to be cleaned, a beater mounted in said nozzle to move inwardly and outwardly through said opening, means for actuating said beater, said beater element involving a span of wire of 90 sinusoidal form disposed over substantially the entire area of said opening, and a 95 shaft disposed at one side of and extending longitudinally of the nozzle opening for pivotally supporting said element in connection with said nozzle.

4. In a nozzle for vacuum cleaners having 95 an opening adjacent the surface to be cleaned, a beater mounted in said nozzle to move inwardly and outwardly through said opening, means for actuating said beater, said beater element involving a span of wire of sinusoidal form disposed over substantially the 100 entire area of said opening, a shaft disposed at one side of and extending longitudinally of the nozzle opening for pivotally supporting said element in connection with said nozzle, said element including an operating arm 105 arranged within the nozzle and extending to the upper end portion thereof and means within the upper end portion of said nozzle for actuating said arm in one direction, and tensional means arranged on the shaft of said element for moving the same in the opposite 110 direction.

In testimony that I claim the foregoing as 115 my invention I have signed my name this 116 17th day of March, 1928.

JOHN C. BREHM.
